DESIGN FOR A PHOTOGRAPHIC FILM PROJECTOR

Alfred M. Davock, Birmingham, Mich., assignor
to The Jam Handy Organization, Inc., Detroit,
Mich., a corporation of Delaware

Application June 5, 1946, Serial No. 130,416

Term of patent 7 years

(Cl. D61—1)

To all whom it may concern:

Be it known that I, Alfred M. Davock, a citizen of the United States, residing at Birmingham, county of Oakland, State of Michigan, have invented a new, original, and ornamental Design for a Photographic Film Projector, of which the following is a specification, reference being had therein to the accompanying drawings, forming a part thereof, in which

Fig. 1 is a front perspective view of a photographic film projector, showing my new design.

Fig. 2 is a front perspective view taken from the opposite side of that shown in Fig. 1.

Fig. 3 is a side elevation of the projector.

I claim:

The ornamental design for a photographic film projector, substantially as shown.

ALFRED M. DAVOCK.
